UNITED STATES PATENT OFFICE.

JONATHAN R. HAMILTON, OF MINNEAPOLIS, MINNESOTA, ASSIGNOR OF
ONE-HALF TO LYMAN R. PALMER, OF SAME PLACE.

SYRINGE.

SPECIFICATION forming part of Letters Patent No. 373,398, dated November 15, 1887.

Application filed June 27, 1887. Serial No. 242,616. (No model.)

To all whom it may concern:

Be it known that I, JONATHAN R. HAMILTON, a citizen of the United States, residing at Minneapolis, in the county of Hennepin and 5 State of Minnesota, have invented certain new and useful Improvements in Syringes for Injecting Cerates, of which the following is a specification.

My invention relates to syringes for injecting cerates or other medicaments into deep cavities, especially in the treatment of ulcerations in the upper portion of the rectum and the lower portion of the sigmoid flexure.

The improvements are illustrated in the accompanying drawings, in which—

Figure 1 is a side view of the improved syringe, and Fig. 2 is a longitudinal sectional view of the same.

A in the drawings represents the barrel of 20 the syringe, and B and C designate the piston and piston-rod, respectively.

D is the discharge-tube connected to the barrel, and is relatively long and preferably somewhat flexible.

25 E is a suitably-rounded head secured on the

end of the tube D, and provided with a number of orifices, e, communicating with the interior chamber, e', of the head.

The syringe may be charged by suction through the orifices e, or its barrel may be 30 filled through an opening, a, in its side. A ring, a', is provided on the barrel for closing the hole a when the syringe has been charged.

The syringe may be constructed of rubber or metal, but preferably of rubber.

What I claim, and desire to secure by Letters Patent, is—

A syringe for injecting cerates, consisting of a barrel having a lateral orifice for introducing cerates thereto, a sliding ring thereon 40 for closing the orifice, a piston and piston rod, and an elongated nozzle having a relatively large rounded head provided with perforations, substantially as and for the purpose set forth.

JONATHAN R. HAMILTON.
